(57) **CLAIM**

The ornamental design for a hockey goalie mask as shown and described.

DESCRIPTION

FIG. 1 is front side perspective view of a hockey goalie mask showing a first embodiment of our new design;

FIG. 2 is a rear side perspective view thereof;

FIG. 3 is a front view thereof;

FIG. 4 is a right side elevational view thereof, the left side elevational view being a mirror image of FIG. 4;

FIG. 5 is a rear view thereof;

FIG. 6 is a top plan view thereof; and

FIG. 7 is a bottom plan view thereof.

FIG. 8 is front side perspective view of a hockey goalie mask showing a second embodiment of our new design;

FIG. 9 is a rear side perspective view thereof;

FIG. 10 is a front view thereof;

FIG. 11 is a right side elevational view thereof, the left side elevational view being a mirror image of FIG. 11;

FIG. 12 is a rear view thereof;

FIG. 13 is a top plan view thereof; and,

FIG. 14 is a bottom plan view thereof.

The broken lines are included to show portions of the hockey goalie mask that form no part of the claimed design.

1 Claim, 14 Drawing Sheets
